CLAIM

The ornamental design for a double-ended sharpening and deburring tool, as shown and described.

DESCRIPTION

FIG. 1 is a perspective view of a sharpening and deburring tool, showing our new design;

FIG. 2 is a right side elevation view thereof, the left side being a mirror image of that shown;

FIG. 3 is a front elevational view thereof;

FIG. 4 is a rear elevational view thereof; and,

FIG. 5 is a bottom plan view thereof.
